E. W. Marshall

ATTORNEY.

UNITED STATES PATENT OFFICE

2,552,694

TOOLHOLDER

Arthur Merrick Stoner, West Hartford, Conn., assignor to The Jacobs Manufacturing Company, Hartford, Conn., a corporation of Connecticut

Application October 29, 1945, Serial No. 625,249

3 Claims. (Cl. 248—1)

1

This invention relates to an improved key holder for connecting a key or wrench to a tool with which it is to be used. It is especially designed to hold the key or wrench for an electrically driven chuck and to form a flexible connection between its electrical conductor and the chuck to maintain the key in a convenient position for use and to prevent the displacement or loss of the key.

Referring to the drawings:

Fig. 1 is a side elevation of a key holder which is made according to and embodies the invention.

Fig. 2 is a sectional front view of the device shown in Fig. 1, the section being taken on the line 2—2 of the latter figure.

Fig. 3 is a side elevation, partly in section, of the device shown in the preceding figures with one of its ends affixed to an electrical conductor and with a chuck key in the other end.

Fig. 4 is a plan view on a larger scale of some of the parts shown in Fig. 3, illustrating the mode of affixing the device to an electrical conductor.

Fig. 5 is a sectional plan of other parts of the device illustrating the mode of affixing a tool to the device.

Fig. 6 is an end elevation of another form of tool which may be held by the device.

The device is an integral piece of resilient material, such as an oil resistant synthetic rubber. One of its end portions, designated by the reference numeral 10, is in the form of a thin walled hollow cylinder having a bore 11 slightly smaller than the diameter of the part of the tool which is to be inserted in it. The other end portion, designated by the reference numeral 12, is in the form of a flat head which has considerably greater transverse width than thickness, in which is a substantially rectangular eye or slot 13, the cross-sectional area of which is considerably smaller than that of the tubular end portion 10. The end portions 10 and 12 are interconnected by a flat strap-like portion, 14, the thickness of which is about one-half the thickness of the head 12 and slightly greater than the smaller dimension of the eye 13. The width of this portion 14 is about double its thickness, and may be uniform throughout its length. For a purpose which will be described, its width is greater than the length of the eye 13. As shown in the drawings, the portion 14A adjacent the head is wider than the length of the eye, and the remainder of this intermediate part of the device is somewhat narrower.

The head 12 is stretched to enlarge the eye 13 therein, and the tubular end portion 10 is passed

2

through the eye. The device is furnished to the user in the condition in which it is illustrated in Figs. 1 and 2 with the strap 14 and 14A in the form of a loop.

5 In affixing the device to an electrical conductor 28, the loop formed by the strap is passed over the conductor and the loop shortened by pulling the strap 14 through the eye. When made as shown in the drawings, the cross-sectional areas 10 of the eye 13 and of the strap 14 are so nearly alike that the strap will slip through the eye easily until the widened portion 14A of the strap reaches the head 12, as shown in Fig. 4. Then a tensional strain is put upon the strap in the direction of the arrow A to stretch the strap. This reduces the cross-sectional size of the portion 14A in Fig. 4 and enables the loop to be tightened upon the conductor. When the tension is released the portion 14A of the strap in the eye tends to resume its original size and becomes locked in the head 12 so that this end of the device is securely affixed to the conductor 28. When the strap is of a uniform width greater than the length of the eye, its cross-sectional size may be similarly reduced by stretching.

30 designates a chuck key which has a shank 31. This is affixed to the device in the following manner: The end of the shank 31, which is somewhat larger than the bore 11, is inserted in the 30 end of the bore, as shown in Fig. 5. Then by squeezing the tubular portion together, as shown at 10A, air is expelled from the bore, after which the shank 31 may be pushed the rest of the way into the bore, as shown in Fig. 3. The shank 31 is then securely affixed to the device. An outward pull on the shank 31 tends to decrease the diameter of the tubular portion 10 and thereby increases the pressure of the bore 11 on the shank and its frictional grip on the shank. Immersing 40 the shank in gasoline or the like facilitates this operation. It makes the shank slippery and has the further effect of partially dissolving the surface of the bore 11, which, upon drying, forms a cohesive bond with the shank.

45 Obviously the device is capable of holding other types of tools. Fig. 6 shows, as an example, a chuck wrench 30A of another type, which has a shank 31 and a hexagonal arm 32 extending at right angles from its outer end. In this figure 50 the end portion 10A is shown narrower than the corresponding part 10 in Figs. 1 and 3, and closed except where the shank 31 is inserted.

Various modifications in construction, mode of operation, method and use of an invention may 55 and do occur to others, especially after benefit-

ing from knowledge of such a disclosure as that herein presented of the principles involved, but the invention itself is not confined to the present showing.

I claim:

1. A tool holder consisting of a single integral elongated piece of resilient material having a head formed at one of its ends, a tool-receiving portion formed at its other end and an intermediate connecting portion, an eye formed in the head, through which eye the tool-receiving portion may be passed to form a loop around an electrical conductor, the cross-sectional area of the part of said connecting portion of the holder adjacent the head being greater than that of the eye and being engaged by pressure exerted upon it by the resilience of the head when it is forced through the eye.

2. A tool holder consisting of a single integral elongated piece of resilient material having a transversely widened head formed at one of its ends, a tool-receiving portion having a cylindrical bore formed at its other end, a rectangular eye of greater width than thickness formed in the head, through which eye the tool-receiving portion may be passed to form a self-locking loop around an electrical conductor, and an intermediate connecting portion, the cross-sectional area of the part of said intermediate connecting portion of the holder adjacent the head corresponding in shape to, but having larger dimensions than those of the eye and being engaged by pressure exerted upon it by the resilience of

the head after said adjacent portion has been forced through the eye.

3. A tool holder consisting of a single integral elongated piece of resilient material having a transversely widened head formed at one of its ends, a hollow cylindrical tool-receiving socket having a continuous wall formed at its other end, a rectangular eye of greater width than thickness formed in the head of substantially the same cross-sectional area as that of the socket, through which eye the socket may be passed to form a self-locking loop around an electrical conductor, and an intermediate interconnecting portion, the cross-sectional area of the part of said intermediate connecting portion of the holder adjacent the head corresponding to, but of larger dimensions than those of the eye and engaged by pressure exerted upon it by the resilience of the head when said adjacent portion has been forced through the eye.
